UNITED STATES PATENT OFFICE.

MARK GINSBERG, OF NEW YORK, N. Y.

DESIGN FOR A PEG FOR TOPS.

48,784.

Specification for Design.

Patented Mar. 28, 1916.

Application filed December 23, 1915. Serial No. 68,454. Term of patent 3½ years.

To all whom it may concern:

Be it known that I, MARK GINSBERG, a subject of the Emperor of Austria-Hungary, residing in New York city, county and State of New York, have invented a new, original, and ornamental Design for Pegs for Tops, of which the following is a specification, reference being had to the accompanying drawing, forming a part thereof.

I claim,

The ornamental design for a peg for tops as shown.

MARK GINSBERG.
